(57) **CLAIM**

The ornamental design for a fastener head cap, as shown and described.

DESCRIPTION

FIG. 1 is a front perspective view showing our new design for a fastener head cap.

FIG. 2 is a back perspective view of the fastener head cap of the present invention.

FIG. 3 is a front view of the fastener head cap of the present invention.

FIG. 4 is a back view of the fastener head cap of the present invention.

FIG. 5 is a right side view of the fastener head cap of the present invention.

FIG. 6 is a left side view of the fastener head cap of the present invention.

FIG. 7 is a top view of the fastener head cap of the present invention; and,

FIG. 8 is a bottom view of the fastener head cap of the present invention.

1 Claim, 6 Drawing Sheets
